Patented Dec. 27, 1921.

UNITED STATES PATENT OFFICE.

JOHN B. NAINTEAU, OF NORTH SMITHFIELD, RHODE ISLAND.

SPINDLE.

1,401,485.

Specification of Letters Patent. Patented Dec. 27, 1921.

Application filed January 17, 1920. Serial No. 352,134.

To all whom it may concern:

Be it known that I, JOHN B. NAINTEAU, a citizen of the United States, residing at North Smithfield, in the county of Providence, State of Rhode Island, have invented certain new and useful Improvements in Spindles; and I do hereby declare the following to be a full, clear, and exact description of the invention, such as will enable others skilled in the art to which it appertains to make and use the same.

This invention relates to spindles and it has for its object to provide a structure in which the bolster of the spindle blade may be finely adjusted and in which the parts when adjusted will be held securely against loosening under working conditions.

A further object of the invention is to provide such construction and arrangement of parts as will insure efficient lubrication and in which the lubricant will be held in such quantity and position as to require attention only at widely separated intervals of time.

An additional object of the invention is to provide a structure of improved form that will insure against lifting of the whirl and therewith the spindle blade, when the bobbin is removed during operation of the apparatus.

Other objects of the invention include the provision of a structure having a minimum of parts easily constructed so that there may be economy of manufacture, further objects and advantages being apparent from the following description:

In the drawings:

Figure 1 is a vertical section through the spindle rail of a spinning machine, together with a spindle embodying the present invention, the spindle blade being in elevation, as also the whirl retainer.

Fig. 2 is a section taken axially and longitudinally through the bolster.

Fig. 3 is a vertical longitudinal section taken centrally through the sleeve that constitutes the spindle base.

Fig. 4 is a detail perspective view of the upper end portion of the bolster.

Fig. 5 is a detail perspective view of the upper end portion of the spindle base into which the upper end portion of the bolster

is fitted with the proper looseness and showing the slots in which the lugs of the bolster are interchangeably received to support the bolster at different elevations with respect to the base.

Referring now to the drawings, there is shown at 10 a portion of the spindle rail of a spinning machine in which there is seated the spindle base in the form of a sleeve 11, the lower portion of which base is threaded at 12 to receive a lock nut 13 that holds the base seated firmly down in the rail with its circumscribing oil cup 14 firmly upon the rail.

Disposed within the sleeve 11 is a bolster including the upper cylindrical portion 15 of major external diameter and the lower cylindrical portion 16 of minor external diameter, the former being slidably fitted within the upper portion of the base sleeve 11, with that degree of looseness common in structures of this character to permit of vibration of the bolster within the sleeve. The lower portion 16 of minor external diameter, is in material spaced relation to the wall of the sleeve, as illustrated.

The bolster is supported within the sleeve 11 and against rotation, through the medium of hanger lugs 17 that radiate from diametrically opposite points of its upper end and which lugs are engaged in a pair of notches 18, 18' or 18'' in the upper end of the sleeve. The notches of each pair are diametrically opposite and extend downwardly of the sleeve, the notches 18' having a slightly greater depth than the notches 18 and the notches 18'' having slightly greater depth than the notches 18'. Thus, by shifting the bolster to engage its lugs 17 with the pairs of notches interchangeably, the position of the bolster vertically within the sleeve may be adjusted. After positioning the bolster within the sleeve, a bushing 19 is screwed into the upper end of the sleeve, which is threaded for that purpose, to position the low end of the bushing in close proximity to the upper end of the bolster, so that while permitting vibration of the bolster, it will prevent the bolster from rising materially under the well known influences that tend to that end.

To facilitate manipulation of the retaining bushing, its upper end portion of the spindle base into which the upper end portion of the bolster

per end is diametrically slotted for the reception of a screw driver, as shown at 20.

The bolster has a central longitudinal bore 21 that receives the usual spindle blade 22, this blade being cylindrical at its portion 22' that fits rotatably the bore of the major portion 15 of the bolster and for which, the bolster constitutes a bearing. Through the minor portion of the bolster, the spindle blade is tapered, as shown at 22" to space it from the corresponding portion of the bore 21, the spindle blade terminating at its lower end where it projects from the bolster, in the cone 22^a.

15 The point of the cone 22^a has a bearing on the hard pin 23 that is driven or pressed into an axial perforation 24 in a cap 25 that is internally threaded and engaged upon the threaded and reduced lower end portion

20 11' of the spindle base sleeve 11. It will be understood that by adjustment of the cap 25, this bearing step member 23 will be raised or lowered to correspondingly adjust the spindle blade 22 or to take up wear of the lower end of the spindle blade. The adjusting cap 25 is held in fixed relation to the spindle base through the medium of a jam nut 26 that is engaged upon the threaded portion 11' of the base above the adjusting cap.

25 The oil cup 14, hereinbefore referred to, circumscribes the spindle base and is formed integral with it and from the bottom of this oil cup there lead the ducts 27 that are inclined downwardly through the inner wall of the spindle base sleeve and which register respectively with ducts 28 that are formed radially through the bolster and open to the bearing surface of the spindle blade.

30 With the arrangement of oil cup described, it will be understood that a part of the lubricant supplied, passes by capillary action upwardly of the cylindrical portion 22' of the spindle blade while the remainder and greater part gravitates either between the spindle blade and the bolster or between the bolster and base sleeve when initially supplied and when the parts are at rest. When, 45 however, the spindle blade is in rotation, the lubricant as needed, passes upwardly of the tapered portion 22" of the spindle blade, by centrifugal action and thus reaches the bearing faces of the spindle blade and the bolster.

50 The whirl employed includes the body 20 having the bore 31 in its upper end portion that fits upon the spindle blade 22 above the base sleeve 11 and below this bore portion 60 31 is the enlarged chamber 32 in which is received the upper end portion of the sleeve 11. The lower end portion of the whirl, directly above its lower extremity, is formed with the coaxial drive pulley 33, below which 65 and in spaced relation is the radiating cir-

cumscribing flange 34, having its rim turned slightly upwardly, as illustrated, with the resultant channeled upper face 35.

70 When a bobbin is raised from the spindle, the tendency is for the whirl and therewith the spindle blade, to rise with it, resulting in dislocation of the parts in general and much consequent annoyance. To prevent this, there is associated with the flange 34, a pivoted stop 36 carried at the side of the oil cup 75 14 and having a hook at its upper end that overhangs the channeled face 35 of the flange 34. If the whirl moves upwardly with the bobbin, such movement will be arrested as soon as the flange 34 strikes the bill 80 of the hook of the stop member. When the whirl is to be lifted off, however, the stop is swung outwardly from its active position, as will be understood.

85 It will be noted that the bore 31 of the whirl is countersunk at its inner end as shown at 31' and that the upper end of the bushing 19 enters this countersink and that the diametrical slot 20 in the upper end of the bushing, terminates short of the lower 90 end of the countersink. The bushing is in marked spaced relation to the spindle blade and thus, such lubricant as may pass above the bolster, will be thrown off centrifugally from the spindle blade and caught within 95 the bushing instead of passing to the whirl and thence downwardly and finally outwardly from it. A body of oil being thus held about the spindle at the upper end of the bolster, the bearing surface of the spindle blade is insured efficient lubrication.

100 It will be noted that the driving pulley 33 circumscribes the spindle blade between the ends of the bearing portions between the blade and the bolster. Thus, the pull laterally of the driving belt is approximately midway of the ends of the portion of the blade that has its bearing in the bolster, with the evident efficiency of result.

105 What is claimed is:

110 1. The combination with a spindle blade, of a bolster receiving the spindle blade and in which the spindle blade is longitudinally and rotatably movable, a sleeve receiving the bolster and a cap for the lower end of the sleeve adjustably connected therewith and having a bearing for the lower end of the spindle blade, the cap being adjustable with respect to the sleeve longitudinally of it and the spindle blade being adjustable with the 115 cap.

120 2. The combination with a spindle base sleeve having seats in its upper end, of a bolster movably disposed within the sleeve and having hanger members movably disposed in the seats, a bushing engaged in the sleeve above the bolster and adjustable toward and away from it, a spindle blade having a bearing within the bolster, and a whirl 125 carried by the spindle blade.

125

130

3. The combination with a spindle bolster, of a sleeve within which the bolster is suspended, a spindle blade having a bearing in the bolster and projecting thereabove, a collar surrounding and in spaced relation to the spindle blade and carried by the sleeve above the bolster in close relation to the latter, and a whirl carried by the spindle and depend-

ing around and below the upper end of the collar.

10

In testimony whereof, I affix my signature, in the presence of a witness.

JOHN B. NAINTEAU.
